UNITED STATES PATENT OFFICE.

WARREN H. STANSBERY, OF GRAND HAVEN, MICHIGAN.

DESIGN FOR A CROCHET-HOOK.

52,973.

Specification for Design.

Patented Feb. 4, 1919.

Application filed March 16, 1917. Serial No. 155,361. Term of patent 14 years.

To all whom it may concern:

Be it known that I, WARREN H. STANSBERY, a citizen of the United States, residing at Grand Haven, in the county of Ottawa and State of Michigan, have invented a new, original, and ornamental Design for Crochet-Hooks, of which the following is a specification, reference being had to the accompanying drawing, forming part thereof, in which:

Figure 1 is an elevation looking at one side of the needle.

Fig. 2 is an under plan view of the needle shown in Fig. 1.

Fig. 3 is an elevation similar to Fig. 1 but looking on the opposite side of the needle and,

Fig. 4 is an enlarged transverse section on the line 4—4 of Fig. 1.

I claim:—

The ornamental design for a crochet hook, substantially as shown.

Signed at Grand Haven this 9th day of March, 1917.

WARREN H. STANSBERY.
